UNITED STATES PATENT OFFICE.

EDSON O. SESSIONS, OF CHICAGO, ILLINOIS.

LOCKING-SWITCH.

1,342,972.

Specification of Letters Patent.

Patented June 8, 1920.

Application filed November 2, 1917. Serial No. 199,972.

To all whom it may concern:

Be it known that I, EDSON O. SESSIONS, a citizen of the United States, residing at Chicago, in the county of Cook and State 5 of Illinois, have invented a certain new and useful Improvement in Locking-Switches, of which the following is a specification.

My invention relates to locking switches of the type known as lock-in lock-out 10 switches which are usually of the single throw type. With switches of this type designed for use in connection with alternating currents of high voltage and large amperage it is necessary to provide positive 15 and strong locking mechanism for holding the switch blades in closed position to prevent large magnetic thrusts exerted on the switch blades tending to open them when for any reason a partial or total short circuit 20 runs the current to a high value.

It is therefore desirable to dispose the locking mechanism so that it engages a retaining device adjacent the contact clip of the switch for holding the switch blade or 25 blades in their closed position, and with switches of this type it is generally desirable to provide locking devices associated with the pivot contact of the switch blade or blades for holding the blades in their open 30 position. For certain constructions of switches of this kind it is possible to employ the same general locking mechanism for engaging the device or catch for holding the switch closed and also to engage the device 35 or catch for holding the switch in its open position. Under other conditions it is impossible to make use of the same general locking mechanism for engaging both catches and it is a purpose of my present invention to produce a locking mechanism that will accomplish 40 the desired results by providing auxiliary locking devices at a distance from the housing containing the main locking mechanism, the auxiliary locking devices being 45 connected with the main locking devices by a connecting rod, so that the auxiliary locking mechanism may be carried by the switch blade between the pivot clip and the contact clip in any position required for 50 a special case. My construction provides that the main locking mechanism and the auxiliary locking devices will be actuated simultaneously by movement of common operating members.

55 My invention will best be understood by reference to the accompanying drawings

showing a preferred embodiment thereof, in which—

Figure 1 shows my complete switch construction in side elevation, 60

Fig. 2 is a front elevation of the parts shown in Fig. 1,

Fig. 3 shows in a view similar to Fig. 1 the same general form of switch mechanism employed as a cut-out switch for an oil 65 switch,

Fig. 4 shows in enlarged front elevation a part of the switch shown in Fig. 3,

Fig. 5 is an enlarged view of a part of the locking mechanism, the wall of the casing 70 containing the mechanism being removed to more clearly show the construction, and

Fig. 6 shows in a view similar to Fig. 5 a modified construction of locking mechanism.

Similar numerals refer to similar parts 75 throughout the several views.

As shown in Figs. 1 and 2 a first support 10 has secured thereto a bracket 11 upon which the pivot clip 12 of the switch is mounted. The switch blade 13 is pivotally 80 secured to the pivot clip 12 at 14 in a position to engage the contact clip 15 carried by a second support 16. The switch blade 13 carries a casing 17 containing the locking mechanism and from the casing a latch 85 18 projects to engage a catch 19 carried by the support 16 to securely lock the switch in its closed position. From the casing 17 there also projects a lever 20 pivotally connected with one end of a connecting rod 90 21, the other end of which is pivotally connected with a second latch 22 pivotally connected to the switch blade 13 at 23. The latch 22 is so disposed that it engages a catch 24 carried by the support 10 when the 95 switch is in its open position.

As more clearly shown in Fig. 5 the casing 17 has formed through its opposite walls slots 25 for receiving a suitable operating tool. The latch 19 is pivotally supported 100 upon a rod 26 carried by the casing and has an extension in which a slot is formed engaging a pin 27 carried by a first operating member 28, which operating member is pivotally supported upon a pin 29 carried by 105 the casing. The operating member 28 is extended beyond the pivot rod 29 in the form of a bell crank lever to overlap the left hand ends of the slots 25 and a compression spring 30 is disposed between the 110 latch 19 and the operating member 28, which spring tends to hold the latch 19 in its lock-

ing position. The lever 20 is pivotally supported upon a rod 31 carried by the casing 17 and is extended beyond the rod 31 to carry a pin 32 engaging a second slot formed 5 in the extension of the latch 19. The lever 20 also carries a second pin 33 engaging a slot formed in the upper end of a second operating member 34 which is pivotally supported in the casing 17 on a rod 35 carried thereby. The lower end of the operating member 34 overlaps the right hand ends 10 of the slots 25.

As a result of the construction described it will appear that motion of either operating member toward the end of the slots 25 15 by a suitable operating tool will move the latches 19 and 22 to their releasing position and that continued motion of the operating tool will serve to move the switch from its 20 closed position to its open position or from its open position to its closed position, depending upon the direction of motion of the operating tool and the initial position of the switch.

25 The ends of the connecting rod 21 are screw threaded into clevises or other connecting devices so that the latch 22 may readily be given different positions of adjustment relative to the lever 20 so that it may properly engage the catch 24.

In the construction shown in Figs. 3 and 4 my improved switch is shown in use as a cut-out switch for an oil switch, the first support 10^a being the lower terminal of the 30 oil switch mechanism while the second support 16^a constitutes the terminal of one of the feeders supplying the oil switch with current. The brackets 11^a and 36 secured to the first and second supports respectively 40 support the pivot clip 12^a and the contact clip 15^a respectively of the switch.

The switch construction is substantially the same as shown and described in connection with Figs. 1 and 2, the principal differences being that there are two switch blades 13^a between which a first block 37 is secured near the free ends of the switch blades for supporting the casing 17 of the locking mechanism and a second block 38 is secured 45 between the switch blades between the pivot and contact clips to support the second latch 22. This construction makes it possible to have the contact clip 15^a engage the switch blades at their extreme ends thus economizing room between the supports 10^a and 16^a which is very desirable in connection with oil switch equipment for the reason that the cut-out switch compartment below the oil switch compartment in the cabinets containing 50 the oil switches is usually of limited height, thus making it necessary to economize the space vertically to maintain as great a striking distance as possible between the conducting parts carried by the supports 10^a 55 and 16^a. On account of the walls of the oil

switch compartment preventing the placing of the operating tool in a vertical position to move the switch to its closed position it is desirable to shape the slots 25, as indicated in Figs. 3 and 5, so that the operating tool 70 when placed at an angle extending upwardly and outwardly from the locking mechanism may effectively operate the operating member 28, which would not be the case were the slots 25 extended perpendicularly to the 75 center line of the switch blades.

While I have shown my invention in the particular embodiments above described it will be understood that I do not limit myself to these exact constructions, as I may 80 employ equivalents thereof known to the art at the time of the filing of this application without departing from the scope of the appended claims.

In the modified construction shown in Fig. 85 6 the switch blade 13^b carries a casing 17^a for the locking mechanism in which casing the latch 39^a is pivotally supported at 40. The latch is extended beyond its pivotal support to form the lever 39^b engaging one end of 90 the connecting rod 21^a in such a manner that the locking latch and the lever constitute an integral structure. A single operating member 41 is pivotally mounted in the casing 17^a at 42 and is provided with a projecting lug 41^b lying to the left of the pivotal supports 40 and 42 in engagement with a corresponding shoulder formed on the latch 39^a. The operating member 41 and the latch 39^a are provided with engaging surfaces 41^c and 39^c to the right of the pivot supports 40 and 42, as a result of which motion of the operating member in either direction on its pivotal support rotates the latch 39^a and thus the lever 39^b around to the left upon its pivotal support. The operating member 41 is extended to overlap the slots 25^a formed through the walls of the casing 17^a and the overlapping end of the operating member contains the opening 42^a 100 in alinement with said slots for receiving an operating tool for actuating said operating member. The other end of the connecting rod 21^a is pivotally connected with a second latch 22^a of substantially the same construction and mounted in substantially the same manner as described above for the latch 22. 105

The connecting rod 21^a is similar to the connecting rod 21 above described and serves substantially the same purpose, the only difference being that the rod is threaded for a greater distance from its upper end shown in Fig. 6 to receive jam nuts 45 against which one end of a compression 125 spring 44 encircling the connecting rod rests, the other end of said spring resting against a bracket 43 secured to the switch blade 13^b near the free end of said blade through which bracket the connecting rod preferably 130 passes. By this construction the number of

parts of the locking mechanism is materially reduced, and furthermore the spring 44 serving to hold the latches in their locking position may be readily adjusted so as to have 5 just the tension required to properly hold the latches in their engaging position.

What I claim is:

1. In a locking switch of the lock-in lock-out type, the combination of a first support, 10 a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally carried by said switch blade between said pivot 15 clip and said contact clip, and a connecting rod between said latch and said locking mechanism, whereby operation of said locking mechanism operates said latch, and a casing carried by said switch blade for containing said locking mechanism, said casing having slots through its opposite walls to receive an operating tool.

2. In a locking switch of the lock-in lock-out type, the combination of a first support, 20 a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally carried by said switch blade between 25 said pivot clip and said contact clip, and a connecting rod between said latch and said locking mechanism, whereby operation of said locking mechanism operates said latch, and a casing carried by said switch blade for containing said locking mechanism, said casing having slots through its opposite walls to receive an operating tool, said locking mechanism comprising a second latch, two operating members overlapping said slots, and devices connecting said members and said second latch with said connecting rod.

3. In a locking switch of the lock-in lock-out type, the combination of a first support, 55 a pivot clip carried by said support, a switch blade pivoted to said pivot clip, a second support, a contact clip carried by said second support for engaging said switch blade in its closed position, a catch carried by said second support, locking 60 mechanism carried by the switch blade engaging said catch when the switch is closed, a second catch carried by said first support, a latch pivotally carried by said switch blade between said pivot clip and said contact clip, and a connecting rod be-

tween said latch and said locking mechanism, whereby operation of said locking mechanism operates said latch, and a casing carried by said switch blade for containing said locking mechanism, said casing having 70 slots through its opposite walls to receive an operating tool, said locking mechanism comprising a second latch, two operating members overlapping said slots, and devices connecting said members and said second latch with said connecting rod, said connecting rod having a threaded end for adjusting 75 the other of said members.

4. In a locking switch of the lock-in lock-out type, the combination of a first support, a pivot clip carried by said support, a switch blade pivoted to said pivot clip, a second support, a contact clip carried by 80 said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a connecting rod between 85 said latch and said locking mechanism, whereby operation of said locking mechanism operates said latch, and a casing carried by said switch blade for containing said locking mechanism, said casing having slots through its opposite walls to receive 90 an operating tool, said connecting rod having a threaded end for adjusting said first latch as desired relatively to said locking mechanism.

5. In a locking switch of the lock-in lock-out type, the combination of a first support, a pivot clip carried by said support, a switch blade pivoted to said pivot clip, a second support, a contact clip carried by 95 said second support for engaging said switch blade in its closed position, a catch carried by said second support, locking mechanism carried by the switch blade engaging said catch when the switch is closed, a second catch carried by said first support, a latch pivotally carried by said switch blade between 100 said pivot clip and said contact clip, and a connecting rod between said latch and said locking mechanism, whereby operation of said locking mechanism operates said latch, and a casing carried by said switch blade for containing said locking mechanism, said casing having slots through its opposite walls to receive an operating tool, said locking mechanism comprising a second latch, two operating members overlapping said slots, and devices connecting said members and said second latch with said connecting rod, said connecting 105 rod having a threaded end for adjusting 110 the other of said members.

6. In a locking switch of the lock-in lock-out type, the combination of a first support, a pivot clip carried by said support, a switch blade pivoted to said pivot clip, a second support, a contact clip carried by 115 said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a connecting rod between 120 said latch and said locking mechanism, whereby operation of said locking mechanism operates said latch, and a casing carried by said switch blade for containing said locking mechanism, said casing having slots through its opposite walls to receive an operating tool, said locking mechanism comprising a second latch, two operating members overlapping said slots, and devices connecting said members and said second latch with said connecting rod, said connecting 125 rod having a threaded end for adjusting 130 the other of said members.

said first latch as desired relatively to said locking mechanism.

6. In a locking switch of the lock-in lock-out type, the combination of a first support, 5 a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a 70 connecting rod between said latch and said locking mechanism, whereby operation of said locking mechanism operates said latch, and a casing carried by said switch blade for containing said locking mechanism, said 75 casing having slots through its opposite walls to receive an operating tool, said locking mechanism comprising a second latch, two operating members overlapping said slots, and devices connecting said members 80 and said second latch with said connecting rod, and a block carried by said switch blade between said pivot clip and said contact clip for supporting said casing.
9. In a locking switch of the lock-in lock-out type, the combination of a first support, a pivot clip carried by said support, a switch blade pivoted to said pivot clip, a second support, a contact clip carried by said second support for engaging said switch blade in 85 its closed position, a catch carried by said second support, locking mechanism carried by the switch blade engaging said catch when the switch is closed, a second catch carried by said first support, a latch pivotally 90 carried by said switch blade between said pivot clip and said contact clip, and a connecting rod between said latch and said locking mechanism, whereby operation of said locking mechanism operates said latch, 95 and a casing carried by said switch blade for containing said locking mechanism, said casing having slots through its opposite walls to receive an operating tool, said locking mechanism comprising a second latch, two 100 operating members overlapping said slots, and devices connecting said members and said second latch with said connecting rod, said slots extending at substantially right angles to said switch blade adjacent one of said members and obliquely of said blade adjacent the other of said members, said connecting rod having a threaded end for adjusting said first latch as desired relatively to said locking mechanism.
7. In a locking switch of the lock-in lock-out type, the combination of a first support, a pivot clip carried by said support, a switch blade pivoted to said pivot clip, a second support, a contact clip carried by 105 said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a connecting rod between said latch and said locking mechanism, whereby operation of said locking mechanism operates said latch, 110 and a casing carried by said switch blade for containing said locking mechanism, said casing having slots through its opposite walls to receive an operating tool, said locking mechanism comprising a second latch, two 115 operating members overlapping said slots, and devices connecting said members and said second latch with said connecting rod, said slots extending at substantially right angles to said switch blade adjacent one of said members and obliquely of said blade adjacent the other of said members, and a block carried by said switch blade between said pivot clip and said contact clip for supporting said casing.
10. In a locking switch of the lock-in lock-out type, the combination of a first support, a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally 120 carried by said switch blade between said pivot clip and said contact clip, and a connecting rod between said latch and said locking mechanism, whereby operation of 125 said locking mechanism, whereby operation of 130

said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a connecting rod between said latch and said locking mechanism, whereby operation of said locking mechanism operates said latch, and a casing carried by said switch blade for containing said locking mechanism, said casing having slots 15 through its opposite walls to receive an operating tool, said locking mechanism comprising a second latch pivotally mounted in said casing, two operating members pivotally mounted in said casing and overlapping opposite ends of said slots, a lever pivotally mounted in said casing and articulating with said second latch, said lever being connected with said connecting rod and said members articulating respectively 20 with said second latch and said lever, a spring tending to hold said latches in their locking position, and a block carried by said switch blade between said pivot clip and said contact clip for supporting said casing.

30 15. In a locking switch of the lock-in lock-out type, the combination of a first support, a pivot clip carried by said support, a switch blade pivoted to said pivot clip, a second support, a contact clip carried 35 by said second support for engaging said switch blade in its closed position, a catch carried by said second support, locking mechanism carried by the switch blade engaging said catch when the switch is closed, 40 a second catch carried by said first support, a latch pivotally carried by said switch blade between said pivot clip and said contact clip, and a connecting rod between said latch and said locking mechanism, whereby 45 operation of said locking mechanism operates said latch, and a casing carried by said switch blade for containing said locking mechanism, said casing having slots through its opposite walls to receive an operating tool, said locking mechanism comprising a second latch pivotally mounted in said casing, two operating members pivotally mounted in said casing and overlapping opposite ends of said slots, a lever 50 pivotally mounted in said casing and articulating with said second latch, said lever being connected with said connecting rod and said members articulating respectively 55 with said second latch and said lever, and a spring tending to hold said latches in their locking position, said slots extending at substantially right angles to said switch blade adjacent one of said members and obliquely of said blade adjacent the other 60 of said members, and a block carried by 65

said switch blade between said pivot clip and said contact clip for supporting said casing.

16. In a locking switch of the lock-in lock-out type, the combination of a first support, a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a connecting rod between said latch and said locking mechanism, whereby operation of said locking mechanism operates said latch, and a casing carried by said switch blade for containing said locking mechanism, said casing having slots through its opposite walls to receive an operating tool, said locking mechanism comprising a second latch pivotally mounted in said casing, and an operating member engaging said second latch and pivotally mounted in said casing. 70 75 80 85 90

17. In a locking switch of the lock-in lock-out type, the combination of a first support, a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally carried by said switch blade between said pivot clip and said contact clip, and a connecting rod between said latch and said locking mechanism, whereby operation of said locking mechanism operates said latch, said locking mechanism comprising a second latch pivotally supported by said switch blade and an operating member engaging said second latch and pivotally supported by said switch blade.

18. In a locking switch of the lock-in lock-out type, the combination of a first support, 115 a pivot clip carried by said support, a switch blade pivoted to said pivot clip, a second support, a contact clip carried by said second support for engaging said switch blade in its closed position, a catch carried by said 120 second support, locking mechanism carried by the switch blade engaging said catch when the switch is closed, a second catch carried by said first support, a latch pivotally carried by said switch blade between said 125 pivot clip and said contact clip, and a connecting rod between said latch and said locking mechanism, whereby operation of said locking mechanism operates said latch, and a casing carried by said switch blade for 130

containing said locking mechanism, said casing having slots through its opposite walls to receive an operating tool, said locking mechanism comprising a second latch pivotally mounted in said casing, and an operating member engaging said second latch and pivotally mounted in said casing, said slots extending in one direction at one end thereof and in another direction at the other end thereof.

19. In a locking switch of the lock-in lock-out type, the combination of a first support, a pivot clip carried by said support, a switch blade pivoted to said pivot clip, a second support, a contact clip carried by said second support for engaging said switch blade in its closed position, a catch carried by said second support, locking mechanism carried by the switch blade engaging said catch when the switch is closed, a second catch carried by said first support, a latch pivotally car-

ried by said switch blade between said pivot clip and said contact clip, and a connecting rod between said latch and said locking mechanism, whereby operation of said locking mechanism operates said latch, and a casing carried by said switch blade for containing said locking mechanism, said casing having slots through its opposite walls to receive an operating tool, said locking mechanism comprising a second latch pivotally mounted in said casing, an operating member pivotally mounted in said casing and overlapping said slots, said operating member engaging said second latch to operate the same, and a lever connected with said second latch, said lever being pivotally connected with said connecting rod.

In witness whereof, I hereunto subscribe my name this 25th day of October, A. D. 1917.

EDSON O. SESSIONS.
